DESIGN FOR A SHAMPOO APRON OR SIMILAR ARTICLE

Neta Mae Tull, Oklahoma City, Okla.

Application February 24, 1938, Serial No. 75,384

Term of patent 7 years

To all whom it may concern:

Be it known that I, Neta Mae Tull, a citizen of the United States, residing at Oklahoma City, in the county of Oklahoma and State of Oklahoma, have invented a new, original, and ornamental Design for a Shampoo Apron or Similar Article, of which the following is a specification, reference being had to the accompanying drawing, forming part thereof.

The figure is a plan view of a shampoo apron or similar article embodying my new design.

The characteristic feature of my design for a shampoo apron or similar article resides in the specific stitching around the neck aperture thereof, as shown.

I claim:

The ornamental design for a shampoo apron or similar article, as shown and described.

NETA MAE TULL.
